BOTTLE OR SIMILAR ARTICLE

Frank J. Benes, Lancaster, Ohio, assignor to Anchor Hocking Glass Corporation, Lancaster, Ohio, a corporation of Delaware

Filed June 7, 1966. Ser. No. 2,597

Term of patent 14 years

(Cl. D58—6)

FIG. 1 is a side elevational view of a bottle or similar article showing my new design;

FIG. 2 is a front end view thereof;

FIG. 3 is a rear end view thereof;

FIG. 4 is a top view thereof; and

FIG. 5 is a sectional view taken along line 5—5 of FIG. 1.

The dominant features of my design reside in the portions shown in full lines.

I claim:

The ornamental design for a bottle or similar article, substantially as shown and described.
